UNITED STATES PATENT OFFICE.

HARRY HAUGH, OF ANDERSON, INDIANA.

DESIGN FOR A TILE.

SPECIFICATION forming part of Design No. 27,842, dated November 9, 1897.

Application filed April 23, 1897. Serial No. 633,557. Term of patent 14 years.

To all whom it may concern:

Be it known that I, HARRY HAUGH, a citizen of the United States of America, residing at Anderson, in the county of Madison and State of Indiana, have invented and produced a new and original Design for the Surface of Encaustic Tiles, of which the following is a specification, reference being had to the accompanying drawings, forming a part thereof.

Figure 1 is a view of the finished face of the tile, and Fig. 2 is a sectional edge view of the same.

The leading feature of this my design consists in a tile which is square in outline and provided with an ornamental raised surface presenting a somewhat mottled or frosted effect.

B is the body of the tile, V is the background, and F is the raised, frosted, or mottled surface, and the said design is confined within the limits of the boundary of the tile, which latter is equal sided and square in outline.

Having thus fully described this my design, what I claim as new and original is—

The design for an encaustic tile, substantially as herein described and shown.

HARRY HAUGH.
